Attorneys

UNITED STATES PATENT OFFICE.

SIDNEY LEE, OF BROKEN ARROW, OKLAHOMA.

MEASURING DEVICE.

Application filed June 14, 1921. Serial No. 477,514.

To all whom it may concern:

Be it known that I, SIDNEY LEE, a citizen of the United States, and a resident of Broken Arrow, in the county of Tulsa and State of Oklahoma, have invented certain new and useful Improvements in Measuring Devices; and I do hereby declare the following to be a full, clear, and exact description of the invention, such as will enable others skilled in the art to which it appertains to make and use the same.

This invention relates to improvements in measuring devices and more particularly to such as are adapted to register the amount of stitching done by sewing machines,—one object of the invention being to provide simple and efficient means which may be readily attached to the head of a sewing machine and which shall be operable from the driving shaft therein to register, through the medium of the rotation of said shaft and the number of stitches effected during each rotation, the amount of stitching accomplished in yards, feet and inches.

A further object is to so construct and arrange the mechanism of the device that two registers of the work done shall be made, one of which registers shall be visible to and controllable by the operator and the other concealed from view and inaccessible to the operator whereby any tampering with the visible registering devices may be detected by the readings of the concealed register.

With these and other objects in view, the invention consists in certain novel features of construction and combinations of parts as hereinafter set forth and pointed out in the claims.

In the accompanying drawings; Figure 1 is a view illustrating my improvements, with the casing shown in section; Figure 2 is a view taken at right angles to Figure 1; Figure 3 is a sectional view on the line 3—3 of Figure 2; Figure 4 is a view in section on the line 4—4 of Figure 2, and Figure 5 is a view in section on the line 5—5 of Figure 2.

In describing the construction of my improved measuring device, I will assume by way of example that the sewing machine will make ten stitches per inch of the goods and that the needle shaft will make three revolutions for each stitch.

A portion of the head of a sewing machine is indicated at 1 and the driving or needle shaft 2 is provided with a gear 9 which may

be secured either to said shaft or to the flywheel 4.

A frame 5 is hinged at one edge to a plate 6 and the latter is adapted to be secured upon the head 1 of the sewing machine. A shaft 7 is suitably supported by the frame 5 and at one end, this shaft is provided with a gear 8 to mesh with the gear 9 and has three times as many teeth as the latter so that the shaft 7 will make one revolution for each stitch. The shaft 7 is provided at its other end with a worm 10 which meshes with a gear 11 on a shaft 12,—said gear 11 having 10 teeth so that it will make one revolution for each inch of stitching. The shaft 12 is also provided with a worm 13 which meshes with a worm gear 14 having twelve teeth so that it will make one revolution for each foot of stitching. The gear 14 is carried by a shaft 15 and this shaft also carries a gear 16.

The shafts of disk registers A and B are mounted in the frame 5 and the shafts of these registers carry gears 17—18 respectively and are spaced apart,—a portion of the gear 16 being disposed between the gears 17 and 18. A bifurcated carrier 19 is pivotally mounted in the frame 5 and supports an elongated pinion 20 which may be made to mesh with the gears 16, 17 and 18 so that motion will be transmitted from the gear 16 to both registers A and B simultaneously. The register A may comprise four disks a, b, c, d. The disk a represents inches so that one revolution of this disk will represent one foot of stitching, this will be transferred to the disk b which represents feet. The disk b is provided with a plurality of sets of numerals "0 1 2" and when this disk b shall have been operated three times by the disk a, the disk c will be moved through suitable transfer means one point,—the disk c thus being intended to indicate yards, and the rotations of this disk c will, by suitable transfer means, operate the disk d which is intended to represent tens of yards. The disks of the register B have the same arrangement as the disks of the register A, but in the register B a greater number of disks may be employed (preferably six) so that a greater aggregate number of yards of stitching may be registered. The register B will be inclosed by a suitable cover B¹ so that it will be inaccessible to the operator, while the register A is visible to the operator and capable of being set by him. The said regis-

ter A may be protected by a suitable covering having a window.

A shaft 21 is mounted in the frame 5 and carries a crank or disk 22 and said shaft is 5 provided with a handle 23 for operating it. A rod 24 is pivotally attached to the crank or disk 22 and after passing freely through an opening in the bottom of the frame 5, is pivotally attached to the base plate 6. A 10 rod 25 is connected at one end to the depending portion of the pivoted carrier 19 and said rod, after passing freely through a slot in the base of the frame 5, is pivotally attached to the base plate 6. It will be ob- 15 served that by turning the manually operable shaft 21 the frame 5 will be moved on its hinged connection with the base plate 6 and the gear 8 will be moved out of mesh with the gear 9, thus disconnecting the de- 20 vice from operative relation to the needle shaft of the machine. It will also be observed that when the frame 5 is thus tilted, the carrier 19 will be turned on its pivotal mounting and the elongated pinion 20 will 25 be moved out of mesh with the gears 16, 17 and 18, thus rendering the registering mechanisms inoperable.

With the use of my improvements, duplicate registers of the number of yards of 30 stitching done by the sewing machine will be made, one of said registers being inaccessible by and out of view of the operator of the sewing machine so that should such operator tamper with the visible register, such tampering would be denoted by 35 comparing the readings of the latter with the readings of the other register.

Having fully described my invention what I claim as new and desire to secure 40 by Letters Patent, is:

1. In a registering device, the combination of a frame, two similar registers mounted therein, one of said registers being visible to the operator and the other register being 45 concealed from view of the operator, means

for actuating said registers simultaneously, and means for disconnecting the actuating means from said registers, whereby one and only one of said registers may be actuated independently. 50

2. In a device of the character described, the combination of a frame mounted for swinging movement, similar registers mounted within the frame, means whereby one of said registers is made visible and the other concealed from view of the operator, a carrier pivotally mounted in the casing adjacent the registers, a pinion mounted in said carrier and adapted to operate both registers, and means whereby swinging of the frame will cause the carrier to move the pinion to or from the registers. 55

3. In a device of the character described, the combination of a base, a frame mounted on the base for vertical swinging movement, a register mounted in the frame, a carrier pivoted in the frame, a pinion on said carrier to actuate the register, and a rod extending through the bottom of the frame and pivoted at one end to the base and at 70 its opposite end to the lower end of the carrier. 65

4. In a device of the character described, the combination of a base, a frame hinged at its rear side upon the base, a shaft mounted in the frame and operable from the exterior thereof, a crank on said shaft, a rod extending through the bottom of the frame and pivoted at one end to said crank and at its opposite end to the base, a register in the frame, and a pinion arranged to actuate the register and movable to or from the same by the swinging of the frame. 75

In testimony whereof, I have signed this specification in the presence of two subscribing witnesses. 80

SIDNEY LEE.
